ARTICLE HOLDER

Robert L. Lyons, Waltham, Mass., assignor to
American Button Sewing Machine Co., Wal-
tham, Mass., a corporation of Massachusetts

Application August 26, 1937, Serial No. 161,030

4 Claims. (Cl. 112—114)

When articles such as buttons, or the like, are being attached to work, as, for example, by stitching, it has been usual to provide a holder for the article to present it in position adjacent to the work while the fastening means for attaching it to the work is being placed. In some cases, however, the work may have projecting portions with which the article holder or a portion of the article itself may contact in such a manner that with holders as heretofore constructed the article has been held out of proper position for its attachment. For example, in the case of the sewing of buttons to garments, it may be desired to position the buttons so near to a seam or other thickened portion of the garment that with the usual holders this thickened portion would prevent the button from being brought against the work, the button or the holder contacting with the thickened portion and being held thereby out of its proper position.

The present invention has for an object to produce an article holder which may conform sufficiently to the surface of the work with which it, or a portion of the article carried thereby may contact, so that the article may be held in proper attaching position regardless of irregularities in the surface of the work due to varying work thickness or other cause. While in its broader aspects not limited thereto, this invention will be further described and exemplified in connection with the securing of buttons to work by a button sewing machine, such an exemplification being shown in the accompanying drawing in which—

Figure 1 is a fragmentary side elevation of a button sewing machine provided with a button clamp embodying this invention.

Figures 2 and 3 are detail sections to a larger scale on lines 2—2 and 3—3, respectively, of Figure 1.

Figure 4 is a detail section on line 4—4 of Figure 2.

Figure 5 is a perspective view of an equalizing element.

Referring to the drawing, at 1 is indicated the work table of a sewing machine having the usual sewing arm 2 upstanding from one end thereof and provided with a sewing head 3 positioned above the work table. This sewing head 3, as shown, supports a needle bar 4 of any suitable description, which may carry one or more needles such as 5. The article to be sewed, shown in Figures 2 and 3 as a button 6, is carried by a button clamp which presents the button in proper relation to the path of the needle 5 so as to sew

the button to goods such as 7 which are supported on the work plate. As shown the button clamp includes a support 8 suitably mounted on the machine, the usual mounting permitting the button clamp to be raised or lowered with respect to work on the work table 1. As shown the support 8 is carried on the forward end of a lever 9 fulcrumed at 10, suitable means such as a chain 11 secured to the forward portion of the support 8 in any suitable manner, being employed to lift the clamp from the work table.

The support 8 has loosely pivoted to its under face a pair of side arms 15 carrying at their forward ends the button clamping jaws 16 which may engage the button 6 on opposite sides. As usual a third rear central jaw 17 may be employed if desired, the jaws 16 and 17 together supporting the button.

The jaw-carrying arms 15, as shown best in Figure 4, are perforated as at 20 at their rear ends for loose engagement on pivots 21 at opposite sides of a median plane of the support 8. This mounting of the arms 15 permits them to swing toward and from each other about the axis of their respective pivot screws 21 and also permits their free ends carrying the jaw members 16 a limited free up and down motion. The arms 15 are connected for simultaneous movement from and toward the median vertical plane of the support 8. For this purpose there is shown a slide 22 (see Figure 2) provided with oppositely inclined slots 23 in which ride pins 24 projecting thereinto from the arms 15. The slide 22 is suitably supported for forward and back motion on the lower face of the support 8 and its forward motion, which is that tending to close the jaws 16 toward each other, may be limited as by an adjustable stop hook 25 secured as by a screw and slot connection at 26 to the top face of the support 8. The forward end of this stop hook 25 is arranged to be engaged by the head 27 of a stop screw 28 of the slide riding in the slot 29 of the support 8. The position of this stop hook determines the extent to which the jaws 16 may approach each other, they being yieldingly urged to this position as by means of a spring 30 (see Figures 1 and 2), the ends of which engage in notches in the sides of the arms 15 and the intermediate portion of which is formed as a loop which extends rearwardly of the arms 15.

Substantially in the central vertical plane relative to which the jaws may swing, there is pivoted, as on the screw 35, an equalizing lever 36, so positioned that suitable portions of the arms 15 or parts carried thereby, herein shown as the

heads of securing screws 37 which fix certain of the jaw elements to the arms 15, may engage therewith when the arms 15 are pushed upwardly to a sufficient extent.

5. The button 6 being placed in position between the jaws 16 and 17 and the button clamp being lowered against the work, should one of these jaws 16 or an adjacent portion of the button engage the work before the other, the downward motion of the jaw first to engage is stopped as shown in Figure 3, while the support is permitted to descend further. The engagement of the screw 37 on that arm which first is stopped by the work then acts to rock the lever 36 as shown 10 in Figure 3, giving an additional downward pressing motion to the opposite arm 15 so as to bring it down against the less elevated surface of the thinner portion of the work. For example, as shown in Figure 3, two layers of the work 7, as in 15 a seam, come beneath one of the jaws 16, while beneath the other jaw is a single thickness of the work. This lever 36 thus acts as an equalizer to insure contact of both of the jaws 16 with the work, thus permitting the button supported between them to be brought down close to the work 20 in position to be sewed thereon, although in a tilted position, as shown in Figure 3. Without this equalizing action the descent of the support 8 would be stopped when either of the jaws first 25 contacted with the work, which in the case of work of unequal thickness would thus hold the button out of contact with the work so that it would not properly be stitched thereto. By the provision of the equalizer, however, both of the 30 jaws may find bearing on the work regardless of surface irregularities due to thickness variations, the button being held therebetween. While the button is in somewhat tilted position, it is so related to the work that it may be properly stitched thereto, even though it is presented closely adjacent to a seam or other thickened portion of the goods which, with clamps as heretofore constructed, would prevent the button from being 35 brought down into proper sewing position. While 40 in Figure 3 the thickened portion of the work is shown as engaged by one of the jaws 16, the left hand jaw being so shown, it will be evident that a similar result would be produced should the button or other article to be attached, rather than one of the clamp jaws, first contact with the work on one side of its axis. It will be noted that the third jaw does not partake of this up and down motion with respect to its support, but since two of the jaws are permitted it, all three 45 jaws coact to support the button or other article in proper position to the work regardless of thickness variations therein.

From the foregoing description of an embodiment of this invention, it should be evident to 50 those skilled in the art that various changes and modifications may be made without departing

from the spirit or scope of this invention as defined by the appended claims.

I claim:

1. In combination with a work table, of a support movable from and toward said table, a pair of arms pivoted to said support to move laterally toward and from each other and loosely to permit limited up and down motion of the free ends of said arms, yielding means tending to press said arms about their pivotal axes toward each other, 10 an article-engaging element carried by each arm, and a lever pivoted to said support and having opposite end portions extending over said arms to be engaged thereby when said support is lowered and equalize pressure of said elements 15 against the work regardless of different thicknesses of work beneath said jaws.

2. In combination, a support, a pair of jaw members mounted on said support to move from and toward each other, connections between said members and support to cause such movement of said members to be equal and opposite with respect to a median plane, the mounting of said jaw members including means allowing limited independent motions of said members substantially parallel to said plane, and a lever fulcrumed substantially in said plane transverse to the direction of said limited motion and operatively connected to said members at certain times to cause motion of one of said members in the direction of its limited motion to produce opposite motion of the other of said members. 20 25 30

3. In combination, a support, a pair of arms loosely pivoted on said support to swing toward and from each other and to a limited extent to move from and toward said support, an element slidably carried by said support and having guiding connections to said arms for producing equal and opposite swing of said arms from and toward each other, a lever fulcrumed on said support and 40 against opposite arms of which said pivoted arms may engage to cause motion of one of said pivoted arms toward said support to move the other pivoted arm away from said support, and article-engaging elements carried at the free ends of said 45 pivoted arms.

4. A button clamp comprising a support, a pair of arms pivoted to side faces of said support with capability of limited up and down motion, button-engaging jaws carried by said arms, means for yieldingly pressing said arms toward each other to hold a button between said jaws, and a lever pivoted to said support and against opposite arms of which said pivoted arms may engage to cause upward motion of one of said jaws to a 50 predetermined point within a predetermined range of motion to move to and hold the other of said jaws in a predetermined lower position with respect to said support. 55
